DESIGN FOR A SACHET

Jean E. Vivaudou and Henry G. Lubin,
New York, N. Y.

Application May 5, 1941, Serial No. 100,779

Term of patent 14 years

To all whom it may concern:

Be it known that we, Jean E. Vivaudou and Henry G. Lubin, citizens of Great Britain and of the United States, respectively, and both residents of New York city, in the county of New York and State of New York, have invented a new, original, and ornamental Design for a Sachet, of which the following is a specification, reference being had to the accompanying drawing, forming a part thereof.

Fig. 1 is a front elevational view of a sachet, showing our new design.

Fig. 2 is a top plan view of the same.

Fig. 3 is a bottom plan view of the same.

We claim:

The ornamental design for a sachet, as shown.

JEAN E. VIVAUDOU.
HENRY G. LUBIN.
